UNITED STATES PATENT OFFICE.

MICHAEL O'CONNOR, OF NEW BRUNSWICK, NEW JERSEY.

SHEET-METAL SCREW-NOZZLE.

SPECIFICATION forming part of Letters Patent No. 299,841, dated June 3, 1884.

Application filed April 18, 1882. (Model.)

To all whom it may concern:

Be it known that I, MICHAEL O'CONNOR, of New Brunswick, in the county of Middlesex and State of New Jersey, have invented certain new and useful Improvements in Sheet-Metal Screw-Nozzles Designed for Employment on Oil-Cans and Analogous Vessels; and I hereby declare that the following is a full, clear, and exact description thereof, reference 10 being had to the drawings which accompany and form part of this specification.

My invention relates to that class of screw-nozzles generally used on metallic cans for the storage and transportation of oil.

Such nozzles as most commonly heretofore 15 used for oil-cans and similar purposes have been formed out of sheet-zinc or other ductile metal capable of being easily worked or spun or struck up into the desired shape, and at the same time possessing sufficient rigidity or 20 stiffness of itself to retain the shape given it under the contingencies of ordinary usage. Nozzles made of such material are, however, comparatively expensive on account of the 25 cost of material possessing the necessary qualities.

The object of my invention, therefore, is to afford means for producing such nozzles economically, utilizing for that purpose a very 30 cheap material, easily worked or manipulated, so that nozzles for the purposes set forth may be put upon the market at a less cost both in material and manufacture than any hitherto used with which I am acquainted. In accomplishing this object I use what is ordinarily 35 known as "taggers tin" for the body of the nozzle, and for the cap thereto. As is well known, this material is quite cheap, but exceedingly thin and without rigidity enough 40 to preserve any shape given it under the contingencies of ordinary use. To avail of its cheapness and to remedy the defects noted, the nozzle is spun or struck up of this material, (taggers tin,) the nozzle being provided 45 with the ordinary shoulder for attachment to the vessel, a screw-threaded body rising therefrom, upon which the cap may be screwed. To stiffen it, a strip of ordinary tin or other similar 50 comparatively stiff sheet metal is taken and a shoulder formed on one edge thereof. It is then bent into a circle and inserted with-

in the nozzle formed of taggers tin, and the two secured together by soldering or by sweating, the re-enforcing-piece thus secured to the nozzle furnishing the stiffness and rigidity requisite to the nozzle. The nozzle should be made of one piece of metal, the web of which extends over and closes what is intended eventually to be the orifice for withdrawing the contents of the vessel. This web, when the vessel has arrived at the point of consumption of its contents, is readily cut away, and a cap used upon the nozzle to thereafter close the orifice. This may be better understood by reference to the drawings, in which—

Figure 1 is a side or front view of a nozzle; Fig. 2, a sectional view showing the re-enforcement alluded to. Fig. 3 is a section of the same with the web cut away, and a side view of the cap to be used with the nozzle. Fig. 4 is a side view, and Fig. 5 a top view, of the re-enforcing collar. Fig. 6 is a strip of metal prior to its formation into such re-enforcing collar. Fig. 7 shows the line of cutting the web over the nozzle when the vessel is first opened.

A, Figs. 1, 2, and 3, represents a screw-nozzle made according to my invention. It is stamped or struck up into shape out of taggers tin, and has the screw-thread *a* formed 80 in it in any of the usual ways. In this condition and for the purpose of imparting to it the requisite rigidity and strength, I insert into it from its under side a flanged collar, *c*, Figs. 2, 3, 4, and 5, made of thicker tin or of other 85 suitable and sufficiently cheap metal, in the outline which is best seen in Fig. 4, which exhibits the external flange, *g*, more clearly than it is shown in the other figures. This flanged collar thus formed I unite to the inner surface 90 of the wall of the nozzle by soldering, or preferably by "sweating," in such manner that the flange *g* of the collar shall come in contact with and preferably adhere to the under side of the flange *b* of the nozzle. When thus combined with the taggers-tin nozzle the latter will possess all the rigidity of nozzles made of the most expensive metal, while its cost of manufacture will be found to be insignificant 95 in comparison with zinc or any other material heretofore employed for these articles.

The collar may be formed in various ways,

but the mode which I prefer, on account of its cheapness, is simply to cut rectangular strips B, Fig. 6, of the requisite length and width out of a sheet of the tin or other metal employed for the purpose, and then stamp or strike up the flange *g* upon one side of it and bend it into the circular form shown in Fig. 5. It is not necessary to solder or otherwise unite the joint *i*, though of course this may be done if desired. But it will be found that when the collar is sweated into the nozzle the joint will be sufficiently closed. If the collar were struck up in its finished circular form out of a sheet of material, a considerable percentage of every sheet would necessarily be wasted. But by making it in the mode described every part of the material will be utilized, and this will greatly increase the economy of production.

As shown in the drawings, it will be seen that the nozzle has no orifice at its upper side, but that the metal of which it is made covers and closes entirely its top surface. This is the means which, as is well known, is generally adopted in cans and vessels of the kinds in which many sorts of screw-nozzles are employed to most completely protect their contents during transportation and storage. But when it becomes necessary, access to the inside of the can may be had by cutting out the interior portion of the taggers tin, forming the

nozzle in the usual way, as represented in Fig. 7. To aid in this a line, *e*, is indented in the web *d* of the nozzle during its formation and near its periphery, affording a guide and easy line of cutting for the cutting-instrument *k*. After the web *d* is cut out, the screw-threaded cap *B* may be used to close securely the vent or opening thus formed.

Having thus described my invention, what I claim as new, and desire to secure by Letters Patent, is—

1. A screw-nozzle consisting of a body of taggers tin or other thin metal formed with suitable screw-threads, and a re-enforcing collar or band of heavier or stiffer metal introduced and secured within the body, substantially as described.

2. A screw-nozzle consisting of a body of taggers tin or other thin metal having a shoulder for attachment to a vessel and formed into a screw-thread upon the part of the body at a right angle thereto, and a re-enforcing band or collar having a shoulder and a body at a right angle thereto, introduced into and secured within the body of the nozzle, substantially as described.

M. O'CONNOR.
